UNITED STATES PATENT OFFICE.

GEORGE H. WADE, OF GREELEY, NEBRASKA.

WAGON-BODY LIFTER.

SPECIFICATION forming part of Letters Patent No. 707,466, dated August 19, 1902.

Application filed November 21, 1901. Serial No. 83,161. (No model.)

To all whom it may concern:

Be it known that I, GEORGE H. WADE, a citizen of the United States, residing at Greeley, in the county of Greeley and State of Nebraska, have invented certain new and useful Improvements in Wagon-Body Lifters; and I do hereby declare the following to be a full, clear, and exact description of the invention, such as will enable others skilled in the art to which it appertains to make and use the same.

This invention relates to the variety of hoisting mechanism specially designed for lifting wagon-bodies, hay-racks, and the like from running-gears to admit of the latter being variously used.

The invention resides in the particular construction of the crane, whereby the upper portion of the post is adapted to be turned and the outer end of the jib capable of vertical adjustment, the parts being braced in their several adjustments.

For a full description of the invention and the merits thereof and also to acquire a knowledge of the details of construction of the means for effecting the result reference is to be had to the following description and drawings hereto attached.

While the essential and characteristic features of the invention are susceptible of modification, still the preferred embodiment of the invention is illustrated in the accompanying drawings, in which—

Figure 1 is a perspective view of a wagon-body lifter constructed in accordance with this invention and showing it in operation, the dotted lines indicating the position of the jib when turned so as to throw the wagon-body out of the way. Fig. 2 is a side elevation. Fig. 3 is a detail view showing the operation of the clamp. Fig. 4 is a detail view of the joint and clamp. Fig. 5 is a view similar to Fig. 4 at a right angle. Fig. 6 is a detail view in perspective of the windlass and adjuncts.

Corresponding and like parts are referred to in the following description and indicated in all the views of the drawings by the same reference characters.

The crane comprises a sectional post and a pivoted jib, the post being mounted upon a suitable base and braced, so as to resist lat-

eral strain. While the base may be of any form and construction, it is shown as consisting of crossed bars or timbers 1 and 2, the 55 post being attached at its lower end to the said base-timbers at their point of crossing. The post comprises a lower fixed section 3 and an upper section 4 in line with the fixed section and mounted to turn thereon about a vertical axis. Within the broad spirit of the invention the manner of journaling the section 4 upon the section 3 is unimportant so long as a substantial joint is formed to resist the weight of the load. In the preferable construction the upper end of the fixed section 3 is ironed, being provided with a metal cap 5, centrally apertured to receive a journal 6, pendent from a metal cap 7, fitted to the lower end of the section 4. The fixed section 70 65 3 is braced by stays 8 and 9, interposed between it and the crossed timbers 1 and 2. The section 4 is stayed by braces 10, having their lower ends firmly connected to the base-timber 1 and their upper ends attached to a 75 ring 11, encircling the section 4 at a point between its ends. By having the section 3 braced in the manner stated and the upper section 4 journaled in a substantial manner to the section 3 and stayed by the braces 10 80 85 the post is firm and not liable to lateral displacement when the crane is supporting the load.

The jib 12 has pivotal connection with the section 4 by means of a pin 13 and is held in 85 the required adjusted position by means of a brace 14, having pivotal connection at its upper end with the jib and adjustable connection at its lower end with the post. This construction admits of the outer end of the jib 90 being vertically adjusted to regulate the lift of the crane for wagons of different height or for any other desired purpose. The lower end of the brace 14 has pivotal connection with a clamp 15, which consists of a band encircling 95 the section 4 and adapted to grip opposite sides of the section at diagonally opposite points of the clamp, the latter being automatic in its action and caused to grip the part 4 with a force proportionate to the weight of the load. The opening of the band 15 is elongated in 100 the plane of the brace 14, the end walls being angling with reference to the sides of the post, as shown at 15^a, so as to grip the post in the

manner stated. Upon lifting the end of the band having the brace 14 attached the opposite end will drop and automatically release the post, thereby permitting the band to be moved up or down to the desired position, and when released the band will assume the position about as shown in Fig. 3 and grip the post and hold the brace 14 and jib 12 in place.

A pulley 16 is mounted upon the pivot-pin 13, and a corresponding pulley 17 is located at the outer end of the jib 12. The hoisting-rope 18 passes over the pulleys 16 and 17 and through a sheave-pulley 19 and has one end attached to the jib 12 and its opposite end adapted to wind upon a windlass 20, journaled to the fixed section 3 of the post. The vertical portion of the hoisting-rope passes through the joint between the sections 3 and 4 of the post and does not in any wise interfere with the free turning of the section 4 when it is required to swing the jib 12 either to the right or to the left. The windlass is provided with a gear-wheel 21, which intermeshes with a pinion 22, secured to a shaft 23, having a crank 24, by means of which the said shaft is rotated for turning the windlass either to the right or to the left, according as it may be required to wind the hoisting-rope upon the windlass or unwind the same therefrom. A detent mechanism co-operates with the shaft 23 to prevent rotation thereof when the crank 24 is released, and this detent mechanism consists of a ratchet-wheel 25 and a pawl 26, arranged for co-operation therewith.

As shown in Fig. 1, the body 27 of a wagon is connected with the sheave-pulley 19 by means of four ropes 28, one being attached to each corner of the body, and after the body has been loosened from the running-gear it can be elevated by rotation of the windlass 20, upon which the lower end of the hoisting-rope is mounted. After the body has been lifted so as to clear the running-gear it may be turned out of the way by swinging the jib 12 either to the right or to the left, so as to occupy the position about as shown by the dotted lines in Fig. 1. The wagon-body may be lowered upon the ground and the crane used for lifting a hay-rack, wagon-body, or other part from the running-gear of another wagon, and the part thus elevated may be in a like manner placed upon the ground out of the way. When it is required to replace the body upon the running-gear, the same can be readily effected without interfering with any other body or part placed upon the ground. The construction is such as to admit of the crane being used in connection with a num-

ber of running-gears, as will be readily comprehended.

Having thus described the invention, what is claimed as new is—

1. In a wagon-body lifter, a crane comprising a jib, hoisting-tackle, a sectional post, and braces, the lower section of the post being fixed and the upper section being journaled thereto to turn about a vertical axis, and braces between the upper turnable section of the post and the support upon which the crane is placed, substantially as set forth. 60

2. In a wagon-body lifter, a crane comprising a jib, hoisting-tackle, a sectional post having its lower portion fixed and its upper part mounted to turn upon the lower section, braces between the lower section of the post and the post-support, a ring fitted to the upper section of the post, and braces between the said ring and the said post-support, substantially as set forth. 75

3. In combination, a sectional post, the lower section being fixed and the upper section mounted to turn upon the lower section about a vertical line, hoisting-rope passing through the joint between the sections of the post, and a windlass journaled to the fixed section of the post and adapted to wind up the hoisting-rope, substantially as set forth. 80

4. In a crane, a post, a jib having pivotal connection with the post, and braces having pivotal connection at its upper end with the jib, and an automatic clamp movable upon the post and having the lower end of the aforesaid braces pivoted thereto, substantially as set forth. 90

5. The herein-described wagon-body lifter comprising a base, a sectional post secured at its lower end to the base and having its upper portion mounted to turn upon the lower fixed portion, a jib pivoted to the turnable section of the post, and braces between the jib and the outer portion of the post and adjustable for varying the elevation of the outer end of the jib, a ring applied to the upper portion of the post, braces between the said ring and base, a windlass applied to the fixed section of the post, and a hoisting-rope passing through the joint between the sections of the post and adapted to have its lower end wind upon the windlass, substantially as specified. 95 100 105 110

In testimony whereof I affix my signature in presence of two witnesses.
